DESIGN FOR A COLLAPSIBLE TUBE BLANK

Hugo Mock, New York, N. Y.

Application May 16, 1942, Serial No. 106,921

Term of patent 7 years

To all whom it may concern:

Be it known that I, Hugo Mock, a citizen of the United States, residing at New York city, in the county of New York and State of New York, have invented a new, original, and ornamental Design for a Collapsible Tube Blank, of which the following is a specification, reference being had to the accompanying drawing, forming part thereof.

In the drawing

Fig. 1 is a perspective view of a collapsible tube blank showing my new design;

Fig. 2 is an inner view of the open end of the tube;

Fig. 3 is a top plan view;

Fig. 4 is a side elevational view.

The characteristic features of my design reside in the portions shown in full lines.

I claim:

The ornamental design for a collapsible tube blank, substantially as shown and described.

HUGO MOCK.
